UNITED STATES PATENT OFFICE.

MARCIAL BRACAMONTE, OF PUERTO CORTES, HONDURAS, CENTRAL AMERICA.

NOISELESS INTERCOMMUNICATING TELEGRAPH AND TELEPHONE DEVICE.

Application filed January 22, 1926. Serial No. 83,019.

This invention relates to noiseless intercommunicating telegraph and telephone devices, and has for its object the novel construction of a soundproof enclosing device 5 with novel arrangements of parts, to simplify and expedite the method of operation of the same.

In the further disclosure of the invention, reference is to be had to the accompanying 10 drawings constituting a part of this specification, in which similar characters of reference denote similar or corresponding parts in all the views, and in which:—

Fig. 1 shows a plan elevation of the device with the top cover open, and part of auxiliary inner partition broken away to show the telegraphic sounder beneath.

Fig. 2 shows a transverse vertical sectional view on the line 2—2 of Figure 1.

Fig. 3 shows a detail of the swinging panel on which telephone is mounted.

Fig. 4 shows an enlarged detail of partition operating device.

Fig. 5 shows a schematic wiring diagram 25 of the device.

The soundproof box 10 has hinged on one of its edges a soundproof cover 11 and is provided with a fixed horizontal inner partition 12, two slidable vertical partitions, one 30 of which partition 13, is normally maintained in an upper position by springs 14 acting against horizontal partition 12, and the other, partition 15, has attached two flexible wires 16 and 17 acting against pulleys 18 and connected to first mentioned vertical partition 13 whereby when partition 15 is drawn up, partition 13 descends and closes compartment 19. The pin 20 and spring 21 is used to lock partition 15 in its 35 upper position, engaging in an aperture of said partition.

Housed in compartment 19 is an adjustable table 22, carrying an ordinary telegraphic sounder 23, and provided with supports 24 operatively engaging the threads of adjusting rod 25, which rod has a bearing at 26 and at 27, and a knob 28 for manual adjusting.

A swinging panel 28' supported in said 50 partition 15 is provided with an ordinary telephone transmitter 29.

Batteries 30 and 31 are suitably arranged within the box 10. The exterior of said box is provided with a telegraph key 32, 55 and other devices explained in detail fur-

ther on in description of the schematic wiring diagram.

Normally in operation the soundproof box has its cover closed, incoming signals 60 actuate the telegraphic sounder, but none of the sounds representing dots and dashes are audible without the soundproof box, telephone transmitter within the soundproof box carries the sounds to exterior earphones 40, and by means of exterior knob 28 the 65 distance between sounder and transmitter may be adjusted to obtain proper loudness in earphones. The transmitter may be used as a telephone by opening box cover 11, drawing up partition 15 which action, 70 because of wires 16 and 17 causes partition 13 to descend and enclose telegraphic sounder in a separate compartment, turning swinging panel so that transmitter faces the front, and proper operation of the switches 75 as explained from wiring diagram.

Referring to Figure 5, a schematic wiring diagram is illustrated which may be used, but I am fully aware that in practice various alterations may be made therein, and 80 therefore I reserve the right and privilege of changing the details without departing from the scope or spirit of the appended claims. The incoming leads from the sender are 33 and 34. Connected to said leads 85 in multiple are the telegraphic sounder 23, an electric bell 35 having switch 36 in series, the secondary coil of transformer 37, and the sending key 32. Connected to said leads in series is the battery 31. The primary 90 of transformer 37 is in series with the primary of transformer 38, the telephone transmitter 29, switch 39, and battery 30. The secondary of transformer 38 is connected with earphones 40. The square 41 95 represents the box 10, and apparatus shown on the outside of said square is supposed to be on the exterior of the box. When switch 36 is closed, switch 39 opened, and key 32 opened the device is in a ready condition 100 to announce an incoming call on leads 33 and 34 by bell 35 ringing.

Receiving operator opens switch 36 and closes switch 39 thereby receiving incoming 105 message on the earphones 40. Talking into transmitter and device can be used as a telephone, and operating key 32 can be used as a telegraphic sender.

Having thus described my invention, 110 what I claim as new, and desire to secure by

Letters Patent of the United States is as follows:—

1. A noiseless intercommunicating telegraph and telephone device comprising a sound proof box having spaced compartments therein, a telegraph sounder disposed within one of said compartments, a telephone transmitter disposed within an adjacent compartment, a slidable partition between said adjacent compartments adapted to be normally retained in a raised position to provide an unobstructed path for the passage of signals from said sounder to said transmitter, a swinging partition adapted to be raised to permit access to said telephone transmitter for transmitting voice therethrough, and means operatively connecting said partition for lowering the slidable partition when said swinging partition is raised to enclose said sounder in a sound proof compartment for preventing interference of the signals therefrom with the voice sounds.
2. A noiseless intercommunicating telegraph and telephone device comprising a sound proof box having compartments therein, a partition disposed between adja-

cent compartments adapted to be raised to permit sound waves from one compartment to pass into the adjacent compartment and to be lowered to prevent the passage of sound when desired, a telegraph sounding device adjustably mounted in one compartment, a telephone transmitter disposed in an adjacent compartment for receiving the sound signals from said sounding device and adapted to transmit said signal outside of said box, ear phones connected with said transmitter and disposed externally of said box, and adjustably supporting mechanism for supporting said sounding device comprising a rod having one end thereof extending outside of said box, said rod being operably connected with said supporting mechanism for varying the position of the sounding device supported thereon relative to the transmitting device for controlling the volume of the sound received by said transmitting device.

In testimony whereof I have affixed my signature.

MARCIAL BRACAMONTE.
